UNITED STATES PATENT OFFICE

EARL G. WATROUS, OF CHICAGO, ILLINOIS

LAVATORY

Application filed March 18, 1929. Serial No. 348,056.

This invention relates to lavatories which are adapted for use in buildings, cars, ships or wherever applicable. Heretofore lavatories have commonly been constructed with 5 the faucets or faucet handles projecting upwardly from the top plate, thereby providing obstructions which are more or less difficult to keep clean and which interfere with the cleaning of the lavatory.

10 In accordance with the present invention, I provide a novel lavatory which is constructed so that the valves or faucets and waste mechanism are concealed and the operating handles are arranged in an elevated 15 position so that they do not interfere with the cleaning of the lavatory.

The objects of this invention are to provide a new lavatory which will be radically different in appearance and construction from 20 those heretofore commonly used; to provide a lavatory having a raised portion at the back providing a shelf for supporting toilet articles or the like; to provide a lavatory with a raised valve chamber having a front wall 25 at the back of the bowl on which the operating members for the valves and waste are mounted; to provide a lavatory made of porcelain or the like with an integrally formed wall projecting upwardly at the back of the 30 bowl for supporting the valve and waste levers; to provide a lavatory having novel supply valves or faucets and means for mounting the same; to provide a lavatory having a drain outlet with a drain valve 35 mounted at the back of the lavatory for controlling the outlet; and such other novel features of construction and arrangement as will be described more fully hereinafter.

40 In the accompanying drawings illustrating this invention

Figure 1 is a plan view;

Figure 2 is a front view;

Figure 3 is a vertical sectional view taken on the line 3-3 of Figure 2;

45 Figure 4 is a sectional view taken on the line 4-4 of Figure 2;

Figure 5 is a sectional view taken on the line 5-5 of Figure 4; and

50 Figure 6 is a detail of the operating lever bearings.

My improved lavatory comprises a bowl 10 having a top plate 11 which preferably extends for a short distance beyond the back of the bowl, as shown in Figure 4. A chamber 12 for some of the operating parts is enclosed 55 by a front wall 13, top or shelf 14 and ends 15. The chamber projects upwardly at the back of the lavatory and the top provides a convenient shelf for receiving toilet articles or the like. The top may be recessed or depressed, as shown at 16, so that such articles will not be likely to slide off.

Hot and cold water may be supplied through inlet pipes 17 and 18 which connect with valves 19 and 20, as shown in Figure 5. 60 These valves are connected together or arranged in a common housing 21 but as the mechanism of the two valves is the same, only one will be described, this being shown particularly in Figures 3 and 4. The pipe 65 18 connects with an inlet chamber 22 in a housing 23 which also has an outlet chamber 24 which is provided with an outlet orifice 25 which connects with a hole 26 leading through the plate 11 into the back of the bowl 10, as shown in Figure 3. The hole 26 is common to the outlets for both the hot and cold water valves. In order to provide a 70 tight closure between the valves and the top of the plate, a gasket 27 is provided and the valve housing or body 21 is pressed downwardly by set screws 28 at the ends thereof which engage with the lower surface of the top or shelf 14.

A shoulder 29 is provided at the inner end 85 of the outlet chamber 24 for receiving a valve seat or disk 30 which is held in position by a valve cage 31 which is formed as shown to allow the water to pass therethrough. A diaphragm 32 engages with the end of the cage 90 and is held securely against the same by a washer 33 and valve body cap 34 which is screwed into the end of the valve body or housing 23. The valve 35 engages with the seat or washer and preferably closes with the water pressure. It is held against the seat by a spring 36 which engages with the valve and with the rear wall of the inlet chamber 22. The valve stem 37 has a collar or shoulder 38 95 which engages with the diaphragm 32, and 100

the end of the stem is threaded for receiving a valve button 39 which presses the diaphragm against the shoulder to make a tight joint. The button 39 passes through a hole 40 in the cap 34 which serves as a bearing to guide the valve.

The valves 19 and 20 project into an opening 41 in the wall 13 which is closed by a cover plate 42. This plate is secured to the valve body housing 21 by screws 43 which pass through the plate and engage with threaded holes in the housing, as shown in Figure 5. The proper distance between the plate and the housing is fixed by distance pieces or lugs 44 on the plate which engage with the front face of the housing. The cover plate 42 is adapted to fit closely around the periphery of the opening and is held by set screws 45 which pass through lugs 46 on the housing 21 and engage with the rear face of the wall 13. This also further serves to hold the housing in position.

The valve 20 is actuated by a valve lever 47 which is pivotally mounted in the cover plate 42, being provided with trunnions 48 which engage with bearings 49 in the plate. These bearings are preferably formed as slots in lugs or projections on the back of the plate, the ends of the projections being pinched or drawn toward each other in order to hold the trunnions after the lever has been placed in position. The lever 47 has an integrally formed segment 50 which fits closely in a slot or opening 51 in the plate, being arranged so that it always keeps the slot closed. The lower portion of the segment has a face 52 which engages with the curved end of the button 39.

The lever 47 preferably extends slightly above the top of the shelf 14 so that it may be conveniently engaged by the finger of the operator. When the lever 47 is pulled outwardly, it forces the valve stem inwardly against the pressure of the spring 36, thereby opening the valve 35 and permitting water to flow from the pipe 18 through the valve chambers and outlet opening 25 and orifice 26 into the bowl. When the lever is released, the spring forces the valve back to closed position and the lever is returned to its normal or upright position. When in this position, the inwardly projecting portion of the segment tends to balance the lever so that it produces little if any pressure on the valve stem which would otherwise tend to hold the valve open.

The valve 19 is provided with an operating lever 53 which is the same as the lever 47, and this valve is actuated in the same manner as above described to permit water to pass from the pipe 17 through the valve and connecting passageways to the bowl.

The bowl 10 has a waste or outlet 54 which is preferably formed integrally therewith, the bottom of the bowl having a screen which is provided by a plurality of small openings 55 leading into the drain. A waste valve

housing 56 is secured to the end of the drain or outlet 54 by means of bolts 57 which pass through lugs on the housing and lugs or projections 58 formed on the bottom of the lavatory, as shown in Figure 2. A waste ring 59 has an annular flange 60 which fits against a shoulder 61 in the waste housing and a gasket 62 is interposed between the ring and housing on one side, and the periphery of the outlet opening 54 on the other side, thus making a tight closure. The outer face of the ring forms a valve seat 63 for a valve 64. This valve is hinged or pivotally connected to an arm 65 of a waste valve lever 66 which projects out through an opening 67 in the top of the housing 56. This lever has a spherical projection 68 which engages with a socket 69 having a bearing or gasket 70 to make a tight joint of the ball and socket character. The lever 66 has a projection 71 which engages with a spring 72, the other end of the spring fitting over a seat 73 in the housing 56. The arrangement of the spring is such that it coacts with the projection to hold the valve in either closed or open position, being arranged to throw over or pass the center, as will be readily understood from Figure 3.

The outer end of the lever 66 is pivotally connected with a rod 74 which passes up through a hole or bearing 75 in the top plate 11 of the lavatory and a bearing 78 in an extension on the housing 21 and is curved at its upper end to engage with a waste lever 76. This lever is pivotally mounted on the plate 42 in the same manner as the lever 47. The lever 76 has a rearwardly projecting arm 77 having a bearing or recess for receiving the end of the rod 74 in order to make a freely operating joint between these parts.

When the lever 76 is pulled outwardly, the arm 77 swings up and raises the rod 74, thereby swinging the lever 66 to open the waste valve and the parts are held in such position by the spring 76. The waste from the bowl passes through the outlet 54 and waste housing 56 which is threaded for connection with any suitable trap or outlet pipe. When the waste is to be closed, the lever 76 is pressed back, thereby depressing the rod 74 and swinging the valve 64 to closed position where it is held tightly against the seat by the spring 72.

While the various parts of my improved lavatory may be made of any suitable material, the bowl and integrally formed parts are preferably formed of porcelain or other ceramic material and the principal valve parts of suitable metal. From this it will be seen that there are no metallic parts projecting over the bowl, and the only exposed parts are the plate with the operating levers mounted thereon which project upwardly so that they do not interfere with the washing or cleaning of the bowl. Furthermore, as there are no metallic parts exposed in the

outlet in the bottom of the bowl, the bowl will have a particularly neat appearance and may be easily kept clean. The lavatory will usually be supported on wall brackets (not shown) against a wall and when so mounted will occupy comparatively little space while providing a convenient shelf for toilet articles. The form of the lavatory may be varied for different conditions or different positions and changes may be made in the construction and arrangement of the parts without departing from the scope of the invention as set forth in the following claims, in which

15 I claim:

1. The combination with a lavatory having an upwardly extending wall at the back of the bowl, of a valve housing mounted at the back of the wall and having valves projecting into an opening in said wall, passageways from said valves to a common passageway into the back of the bowl, a plate covering the opening in the wall, and valve levers mounted on said plate and coacting with the 25 valves for actuating the same.

2. A lavatory construction comprising a bowl having an upwardly extending valve chamber at the rear thereof, a valve housing having two supply valves therein, inlet 30 pipes leading to the respective valves, outlets leading to an inlet orifice directed into the bowl, means for pressing the valve housing downwardly to make a tight closure between the outlet and the bottom of the chamber, a plate fitting over an opening in the front of the chamber, means for securing the plate to the housing, screws engaging with the housing and the wall of the chamber for drawing the plate against the wall, 35 and valve levers pivotally mounted in the plate and operatively connected with the valves for actuating the same.

3. The combination with a lavatory having an upwardly extending valve chamber at the back thereof, of a valve body in said chamber, an inlet pipe connected with the valve body, an outlet opening through the bottom of the valve body said lavatory having a hole leading from the outlet to the 40 bowl, a gasket between the valve body and the bottom of the chamber, means engaging with the body and the top of the chamber for pressing the body downwardly, a spring 45 pressed valve in said valve body having a forwardly projecting stem, said chamber having a hole in the front wall thereof through which the valve body is exposed, a plate covering said hole, means for connecting the plate to the valve body, screws in the valve body which engage with the rear face of the 50 front wall of the chamber, valve levers pivotally mounted in said plate and projecting upwardly adjacent to the chamber, each lever having a segment fitting in a hole in the plate and engaging with a valve stem, the

arrangement being such that when the lever is pulled outwardly the segment will open the valve.

4. A lavatory construction comprising a bowl having an upwardly extending chamber at the rear thereof with a substantially flat top, valves mounted in said chamber, means for supplying water to said valves, passageways from the valves to the lavatory and valve operating devices mounted on the front of the chamber and adapted to coact with said valves.

5. The combination with a lavatory outlet, of a waste housing, a ring interposed between the housing and outlet and providing a valve seat, a valve lever pivotally mounted in said housing, a valve carried by said lever and adapted to coact with the seat, a spring coacting with the valve lever and adapted to hold the valve in either open or closed position, and means connected with the valve lever for swinging the same to open and close the valve.

6. The combination with a housing having a valve seat therein, of a valve coacting with said seat, a lever projecting through an opening in the housing, a ball and socket joint between the lever and the housing, said lever having one arm connected with the valve, a spring engaging with the valve lever and the housing and tending to hold the lever with the valve in either open or closed position and tending to press the lever against its bearing in the housing, and means for swinging the lever to actuate the valve.

7. The combination with a lavatory, of a waste housing connected with the outlet and having a valve seat therein, a valve lever projecting through the housing and having a ball and socket joint therewith, a spring having one end engaging with the housing and the other engaging with the lever to hold the lever in position, said spring also serving as an overthrow to hold the valve in either open or closed position, a rod connected with the lever and extending upwardly to a point above the lavatory, and an operating lever pivotally mounted above the lavatory and connected with said rod for actuating the outlet valve.

8. In a lavatory construction, the combination of a bowl having an integrally formed upwardly projecting wall at the back thereof, valves for controlling the supply to said bowl, valve actuating levers mounted at the front of said wall, a valve for controlling the waste from the lavatory, an actuating lever mounted adjacent to said valve levers, and means for connecting the last named lever with the waste valve.

9. A waste control for a lavatory comprising a chamber having an inlet opening, a ring fitting in said opening and having a valve seat, a lever projecting through the top of the chamber and having an annular bearing thereon engaging with a socket in the cham-

ber, a valve connected with one arm of said lever and adapted to engage with said seat, a projection on said lever, a projection in the casing, a compression spring interposed between said projections and adapted to hold the lever bearing against the socket, said spring also serving as a resilient overthrow to hold the valve in open or closed position.

10. A valve comprising a casing having an inlet chamber and an outlet chamber with inlet and outlet openings, a washer between the inlet and outlet chamber having a valve seat therein, a valve cage engaging with the washer, a diaphragm engaging with the cage, 15 a cap for the outlet chamber which holds the cage and adjacent members in position, a valve in the inlet chamber which engages with the seat in the valve washer, a spring between the valve and the opposite wall of 20 the inlet chamber which tends to hold the valve in closed position, a stem on said valve which projects through the diaphragm and through an opening in the cap, means for making a tight closure between the stem and the diaphragm, and means for pressing the 25 stem to open the valve.

11. In a device of the character set forth, the combination of a valve body having an inlet chamber and an outlet chamber, a washer engaging with a shoulder at the bottom of the outlet chamber and forming a partition between said chambers, a cage engaging with the washer, a diaphragm having its outer periphery engaging with the cage, a washer 35 engaging with the diaphragm, a threaded cap for the outlet chamber which engages with the last named washer for pressing the parts of the chamber together, a valve in the inlet chamber which engages with a valve seat in the washer, a spring tending to hold 40 said valve in closed position, a stem on said valve which projects through the diaphragm, a shoulder on said stem engaging with one side of the diaphragm, a threaded button on 45 the outer end of the stem which engages with the opposite side of the diaphragm to make a tight closure, a bearing in said cap through which the button projects, a lever pivoted adjacent to the button and having a projection for engagement therewith for opening 50 the valve.

EARL G. WATROUS.
